UNITED STATES PATENT OFFICE.

WASHINGTON LAYCOCK, OF CHICAGO, ILLINOIS.

PRINTING-STAMP.

No. 827,982.

Specification of Letters Patent.

Patented Aug. 7, 1906.

Application filed June 3, 1905. Serial No. 263,587.

To all whom it may concern:

Be it known that I, WASHINGTON LAYCOCK, a citizen of the United States, residing at Chicago, in the county of Cook and State 5 of Illinois, have invented certain new and useful Improvements in Printing - Stamps; and I do hereby declare that the following is a full, clear, and exact description thereof, reference being had to the accompanying 10 drawings, and to the letters of reference marked thereon, which form a part of this specification.

This invention relates to improvements in printing-stamps of that class provided with 15 individual types, usually made of rubber, which are separately set into type-receiving slots of a suitable holder, and refers more specifically to improvements designed to afford adjustability with respect to the width of the 20 type-receiving slots and the distance apart of said slots and provide for type of different widths and to also provide for variable spacing of the lines of type of the same or different sizes.

25 The construction herein shown is embraced within the scope of the invention claimed in my prior United States Letters Patent, No. 796,131, granted August 1, 1905, the present improvements relating more specifically to 30 the manner of mounting the type-bars, between which are formed the type-receiving slots, and to the means for maintaining the adjusted position of the bars to provide type-receiving slots of varying width and varying 35 distances between the set-up lines of type in the holder.

The invention consists in the matters hereinafter set forth, and more particularly pointed out in the appended claims.

40 In the drawings, Figure 1 is a side view, partially broken away, of a hand-stamp embodying my improvements. Fig. 2 is a longitudinal section thereof. Fig. 3 is a transverse section thereof. Fig. 4 is a bottom 45 plan view of the stamp, showing the manner of arranging the type therein. Fig. 5 is a detail sectional view taken on line 5 5 of Fig. 1.

As shown in the drawings, A designates the body or back of the stamp, herein shown as 50 having the form of a hand-stamp provided with a handle A'. Fitted to said body is a type-holding frame, herein shown as made rectangular and comprising side members B

B and end members B'. The side and end margins of the body of the stamp are rabbeted 55 to receive the said side and end members of the type-holder frame. C C designate bars supported in said frame and between which are formed longitudinal type-receiving slots c, that receive the types D. The said bars 60 hold the types from lateral movement and act as guides to permit the type to separately yield rearwardly in the manner hereinafter described. The said bars C are mounted in the frame by being provided with hooked 65 ends c' c', which hook over and are thereby connected with transverse bars B² B³, one at each end of the type-holding frame. Said bars B² B³ are so mounted that the distance between the same may be increased or decreased, whereby may be effected a clamping 70 action on the hooked ends of the type-bars in such manner as to frictionally hold them from lateral movement and maintain the width of the type-receiving slots. Various 75 means may be employed for effecting such clamping action of the bars B² B³ with the type-bars. As herein shown, the bar B² extends transversely between and is permanently fixed at its ends to the side members 80 B B of the type-holding frame, while the bar B³ is fixed to an extension-frame B⁴, slid able on the main frame. Said extension-frame comprises a bar parallel with and located outside of the end member B' of the main frame 85 adjacent to the movable clamping-bar B³. It is provided with arms b b, which are located outside of the side members of the type-holder frame B of the type-frame, and the end of the movable clamping-bar B³ extends 90 outwardly through elongated slots b' in the side members B and are affixed to said arms b of said extension-frame. Clamping-screws E E, extending through and having screw-threaded engagement with said extension-frame and bearing at their inner ends against the adjacent end member of the type-holding frame, act when turned inwardly to separate the clamping-bars and produce the frictional engagement between the same and the hooked 95 ends of the type-bars to hold the type-bars from lateral movement. The types D, which are confined in said type-holding slots, are of that character as shown in my aforesaid application, they being provided at the rear of 100 the type-bars with outwardly-facing shoul-

ders which bear against the type-bars. The said shouldered parts of the type are confined between said type-bars and a suitable cushion F, which is fixed to the lower side of 5 the back or body A of the stamp. In this manner the type are held from movement longitudinally of the type-slots. The type-bars do not engage with a clamping pressure, the narrow ends of the types extending between the same; but said bars are so adjusted 10 that the type yield rearwardly into the cushion when a printing pressure is applied to the stamp, the types at this time having guiding engagement with the bars. When said printing pressure is released, the types are forced 15 forwardly into their printing positions by the action of the yielding cushion. During the printing operation of the stamp the body or back moves toward the type-bars, so that 20 while permitting yielding of the type backwardly into said cushion at the same time causes the cushion to be advanced toward the type, and thus afford a proper backing to produce a uniform impression of the types, 25 notwithstanding irregularity of the surface printed upon or irregularity in the lengths of the types.

Any suitable means may be employed for 30 clamping the type-holder frame to the body of the stamp. As herein shown, said type-holder frame is provided at its ends with bails F, which swing over the ends of the back or body of the stamp when the latter is fitted to the frame. The said bails are made of such 35 length that when swung upwardly into their holding positions clamp the stamp body or back to the frame in a manner to exert a pressure of the yielding cushion against the backs of the types, for the purpose hereinbefore described. It will be observed that 40 when the holding or confining bails are thrown downwardly the back or body of the stamp and the cushion attached thereto may be readily removed from the frame, so as to permit 45 access to the rear of the type-holding slots for removing and setting the types therein. The removal of the types is effected after the clamping mechanism for the bars has been released, so as to permit the bars to be 50 slightly separated.

It is obvious that my invention may be embodied in other forms of construction than that shown without departing from the spirit and scope of the invention, and I do not wish 55 to be limited to the structural details except as hereinafter made the subject of specific claims.

I claim as my invention—

1. In a printing-stamp, a type-holder 60 frame, including a plurality of bars between which are formed type-receiving slots, clamping-bars in said frame with which the type-bars have interlocking connection, by means permitting movement of the type-bars to-

ward and from each other, and means for 65 spreading apart the clamping-bars to effect endwise clamping action on the type-bars.

2. In a printing-stamp, a type-holding frame, including a plurality of bars between which are formed type-receiving slots, clamping-bars in said frame which are movable toward and from each other, hooks on the type-bars which hook over said clamping-bars and means for adjusting the clamping-bars toward and from each other. 70

3. In a printing-stamp, a type-holding frame, including a plurality of bars between which are formed type-receiving slots, clamping-bars in said frame, hooks on the type-bars which engage said clamping-bars and laterally slidably thereon, and clamping means for spreading apart the clamping-bars. 75

4. In a printing-stamp, a type-holder including a plurality of bars between which are formed type-receiving slots, clamping-bars in said frame, one of which is affixed to the frame and the other of which is movable therein toward and from the other bar, interlocking connection between the ends of the type-bars and said clamping-bars and means for spreading apart said clamping-bars to effect clamping action between the same and the type-bars. 80

5. In a printing-stamp, a type-holder embracing a type-holding frame including a plurality of bars between which are formed type-receiving slots, clamping-bars in said frame, one of which is fixed in the frame and the other of which is movable in the frame toward and from the other bar, interlocking connections between the ends of said type-bars and said clamping-bars, said frame having slots through which the ends of the movable clamping-bar extend, an extension-frame connected with the movable bar and clamping-screws passing through the extension-frame and engaging the main frame for spreading apart the clamping-bars. 90

6. A printing-stamp comprising a back or body provided on its under face with a cushion, a type-holding frame which is connected with the back by means permitting it to move toward and from the back during the printing pressure of the stamp, said frame embracing a plurality of type-bars between 110 which are formed type-receiving slots, and means effecting endwise clamping pressure on the ends of said bars for holding the bars at predetermined distances apart and to maintain in adjustment the width of the type-slots. 115

7. A printing-stamp comprising a back or body provided on its under face with a cushion, a type-holding frame which is connected with the back, said frame embracing a plurality of type-bars between which are formed type-receiving slots, means for effecting endwise clamping pressure on said bars for hold- 125

ing the bars at predetermined distances apart and to maintain in adjustment the width of the type-slots, and means for holding the said frame to the said back or body comprising bails connected with said frame and adapted to swing over the ends of said back or body and constructed to clamp said cushion against types in said slots.

In testimony that I claim the foregoing as my invention I affix my signature, in presence of two witnesses, this 12th day of April, A. D. 1905.
